Japan, a corporation of Japan
Filed Apr. 30, 1963, Ser. No. 276,782
4 Claims. (Cl. 207—4)

The present invention relates to improvements in the apparatus for manufacturing power cables, more particularly oil-filled cables.

Oil-filled cables are filled with insulating oil of low viscosity by means of oil passages. In manufacturing such cables there are two processes, one of which is that the cable core is sufficiently dried at first in an enclosed drying casing, then a sheath of lead or aluminum is applied, and the sheathed cable is then heated from outside to extract air and moisture from each end (this heating is called the secondary drying, while the drying before applying the sheath is called the primary drying, then insulating oil is filled in the sheath. According to this process, the cable core is exposed to open atmosphere while the sheath is applied, so that it needs the secondary drying. However if in this process the cable core was to be protected from the atmosphere, the secondary drying could be dispensed with.

The second process is to dry the cable core to high degree, impregnate it with refined and de-gassed insulating oil, and successively apply thereto the sheath. According to this process, different from a solid cable, it is necessary to carry out the process without contacting oil-impregnated cable core with external atmosphere by connecting the drying and oil impregnating casing with a press or an extruder of sheath by means of airtight tube.

The present invention relates to an apparatus for carrying out the first process without the secondary drying, or for carrying out the second process. The apparatus comprises an enclosed casing for drying the cable core and impregnating it with insulating oil, a press or an extruder for applying sheath to the cable core, a communication tube hermetically connecting said casing and said press or extruder for passing the core therethrough, and a cable guide device for leading the core from the casing through the communication tube to the press or extruder without contacting the core with external atmosphere, wherein the cable guide device consists of a plate valve, tension wires, etc. Said plate valve is pressed on the inner flange provided in the communication tube to hermetically seal the casing and the press or extruder. When the cable guide device is pulled through the press or extruder, the plate valve is deformed and can pass through the nipple holder and nipple in the press or extruder.

For a better understanding of the invention reference is made to the accompanying drawings, in which

FIGS. 1 and 2 are sectional side elevations of two embodiments of the apparatus of the invention for manufacturing power cables;

FIGS. 3 to 6 are partial sectional views of the essential parts of the apparatus of the invention illustrating several modifications.

Referring to the drawing, 1 represents an enclosed casing in which the cable core 2 is either dried or dried and impregnated with insulating oil. 3 represents a press or an extruder for extruding lead or aluminum to cover the cable core. In accordance with the invention, the casing 1 and the press or extruder 3 are connected with a communication tube 4 hermetically, and cable guide device 5 is provided in the tube to pull the cable core

2

from the casing 1 into the press 3 without contacting external air. In guiding cable core 2, which is either dried or dried and impregnated with insulating oil, to the press or extruder 3 without contacting external air, the construction of the cable guide device poses a problem and it is constructed as follows according to the invention.

FIG. 3 shows an embodiment of the invention more clearly, wherein a plate valve 7 is secured to one end of a tag 6 by eye bolt 8 and bolts 9, 9', etc. and also to one end of the cable core by means of a tension wire 16. The plate valve 7 is located at the flanged portion 13 of the tubes 11 and 12 to airtightly partition them off. In order to lead the cable core 2 into the press or extruder 15 by means of said cable device, the tension wire 16 connected to the tag 6 is pulled out through the nozzle of the press or extruder 3 as shown in FIG. 1. The plate valve 7 is at first pressed on the flange 10' at the left side of FIG. 3, and the casing 1 is evacuated. The plate packing 7 is pulled by the negative pressure to make tight contact with the flange 10', thereby tightly sealing the casing 1; thus the casing 1 is evacuated and dehydrated by suitable means and the cable core is dried thoroughly. Then insulating oil is filled in the casing 1 by suitable means and the gradually pressurized. When the pressure in the casing 1 is raised, the plate valve 7 is pressed to the right side to make contact with the opposite flange 10, so that the flowing out of insulating oil is prevented by partitioning off a chamber 14 in the tube 11 from a chamber 15 (refer to FIG. 3).

Next, the tension wire 16 as shown in FIG. 1 connected to the tag 6 is lead out through the press or extruder 3 where the sheath 30 is sealed at 17 securing the tubes 11 and 18 and a pressure regulating device 19 in position. The inside of the tube is evacuated by means of the pressure regulating device 19 and the moisture is thoroughly removed. Then the insulating oil is fed therein from a previously arranged oil tank (not shown) to make the oil pressure almost equal to that in the chamber 15 inside of the tube 12, thus the pressures on opposite sides of the plate valve 7 become almost equal to each other, so that the plate valve 7 is made free to communicate both chambers. Under such conditions, when the press or extruder 3 is operated to pull out the tension wire 16, the plate valve 7 is deformed, and pulled out together with the tag 6 through the tubes 11 and 18 and the press or extruder 3, so that the cable core 2 can be covered with lead or aluminum sheath without contacting external air.

The shape of the plate valve is not necessarily limited to a plate. FIG. 4 illustrates another embodiment of the cable guide device used in the invention, wherein the plate valve 7 is funnel-shaped. With such construction, the valve effect between plate valve 7 and flanges 10, 10' is further improved. It has an advantage that when the tag 6 is shifted to the side of the press or extruder 3, the plate valve 7 can be deformed more easily.

FIG. 5 illustrates further embodiment of the cable guide device wherein the plate valve 7, similar to that of FIG. 3, is rigidly connected to the tag 6 by eye bolt 8 and bolts 9, 9', etc., and also to one end of the cable core by means of a tension wire 16', and the plate valve 7 is located between flanges 10 and 10' tightly fitted to either one of them according to the pressure difference, same as in FIG. 3. In this case, grooves 20 and 20', annular and otherwise shaped, are provided in the flanges 10 and 10' respectively and are connected through pipes 23 and 23' to vacuum devices 22 and 22' respectively. With such construction and arrangement, when the chambers 14 and 15 inside the pipes 11 and 12 respectively are to be separated, the groove 20, for instance, is evacuated by the vacuum device 22 and the plate valve 7 is sucked by the negative

pressure to firmly contact with the flange 10, so that much more excellent packing effect can be obtained than in the case of FIG. 3.

FIG. 6 illustrates a modified form of FIG. 5 wherein the vacuum devices 22 and 22' are dispensed with by connecting the grooves 20 and 20' by means of pipes 24 and 24' respectively to the chambers 14 and 15 directly. When the chamber 14 or 15 is evacuated, the groove 22 or 22' can be evacuated at the same time, thereby assisting the more rigid contact of plate valve 7 with the flange 10 or 10'.

In cable guide devices as shown in FIGS. 3 to 6 the plate valve 7 is made to tightly contact with either side of the flange 10 or 10'. If it is used under such condition that when one of the chambers 14 and 15 is always at a lower pressure than the other, either one of the flanges 10 and 10' is sufficient.

Two or more such cable guide devices can be used also in series.

The plate valve used for the apparatus under the invention will produce more satisfactory results if its average thickness is $\frac{1}{2}$ inch or under.

According to the apparatus of the invention, the cable core 2 can be pulled towards the press or extruder 3 by means of a tension wire 16 by using a cable guide device 25 having plate valve 7 and tag 6 as shown in FIG. 1. Yet it can be more positively shifted by using a magnetic device as shown in FIG. 2, wherein the tube 18 is made of a non-magnetic material such as brass pipe, and an iron core 25 is connected to the tag 6 by the tension wire 16. The iron core 25 is connected via a rigid rod 26 with a plug 27. Tag 6 having plate valve 7 is connected to the end of cable core 2, and a solenoid 29 is provided outside of the tube 18 at a position corresponding to the iron core 25.

When the above described device is used to shift the cable core 2 to the press or extruder 3, the press or extruder is operated at first to extrude the sheath 30 and airtightly seal an end 31, then the tubes 11, 18 and the sheath 30 are evacuated by the pressure regulating device 19, and afterwards solenoid 29 is energized and shifted towards the press or extruder 3 moving iron core 25 in the same direction; then the plug 27 can be inserted into the sheath 30. The plug 27 inserted into the sheath 30 is tightly fixed to the latter and pulled out of the press or extruder 3. The cable core 2 connected to the plug 27 can be led into the press or extruder 3 to apply a sheath thereon without contacting external air. In this case, the solenoid 29 is de-energized as soon as insertion of the plug 27 is completed.

In the foregoing, description is made of the case where the cable core is only dried, but when the cable core is dried and impregnated with insulating oil, the above described operation may be carried out after the communication tube is evacuated and then filled with insulating oil.

The solenoid can be energized under the fixed condition instead of shifting the solenoid to the side of the press as explained with reference to FIG. 2; if the solenoid 29 is located nearer to the press or extruder 3 than the position of iron core 25 in FIG. 2 and is energized after the preparation is ready as above described, the iron core 25 can be pulled towards the solenoid, thereby inserting the plug 27 into the sheath 30.

When the cable core is impregnated with insulating oil, the plug 27 in FIG. 2 is located in the nipple 32 instead of in the nipple holder 33. Only in this case, plug 27 is so made as to fit well into the nipple 32. The solenoid 29 is arranged on the outside of the iron core 25 which is held at that position by energizing the solenoid. Under

5 this condition the inside of tubes 11, 18 and sheath 30 is evacuated, then insulating oil is filled in the tubes 11, 18 and nipple holder 33 to reach the back of the plug 27, the oil is subjected to pressure, the solenoid is de-energized to release its holding force and the plug 27 is forced into the sheath 30 by the oil pressure to pass the cable core through the press.

According to the device of the invention as above described, when the cable core is dried by means of a drying apparatus or when it is dried and impregnated with insulating oil by means of drying and impregnating apparatus, the plate valve which is a part of the cable guide device is used to interrupt the cable core from external atmosphere, and, thereafter when the sheath is applied by means of a press, the tag connected with the plate valve is further connected with the tension wire, or alternatively an iron core having a plug connected via the rod to the tag, and the iron core can be pulled into the press by magnetic force worked via the non-magnetic tube by the solenoid, without contacting the cable core with external air.

20 This being the case, it is possible to manufacture with high efficiency cables of excellent electrical properties.

What we claim is:

1. An apparatus for manufacturing power cables which comprises in combination, a casing for drying the cable core and impregnating it with insulating oil having an outlet opening therein, a press having a nipple and a nipple holder for applying metal sheath to the cable core, a communication tube between said casing outlet opening and said press, hermetically connected to them to pass said core therethrough, spaced parallel flanges between said casing outlet opening and said communication tube, a cable guide device for leading said core from said casing through said communication tube to said press without contacting said core with external air, a vacuum pump connected to said communication tube, said cable guide device consisting of a plate valve attached to seal the outlet opening of the casing and a tension wire connected to said plate valve, said plate valve contacting with the flanges of the casing outlet opening and said communication tube, said plate valve being so constructed as to deform when pulled by means of the cable guide device passing through said communication tube and the nipple holder and nipple in said press.

45 2. An apparatus for manufacturing power cables according to claim 1, wherein the flanges at the jointing ends of said casing and said communication tube are each provided with such a groove as ensures tight contact of the plate valve and the flanges through evacuation of it.

3. An apparatus for manufacturing power cables according to claim 1, wherein said plate valve is funnel shaped.

50 4. An apparatus for manufacturing power cables according to claim 1, wherein a portion of said communication tube is made non-magnetic, said cable guide device comprises an iron core connected to a rod fixed to a plug, and a solenoid is provided outside of said non-magnetic communication tube to shift the iron core to the press.
